Watson E. Coleman

UNITED STATES PATENT OFFICE.

WILLIAM A. FETSCH, OF ST. PAUL, MINNESOTA.

GUARD FOR MATCH-BOXES.

1,265,069.

Specification of Letters Patent.

Patented May 7, 1918.

Application filed March 17, 1917. Serial No. 155,578.

To all whom it may concern:

Be it known that I, WILLIAM A. FETSCH, a citizen of the United States, residing at St. Paul, in the county of Ramsey and State of 5 Minnesota, have invented certain new and useful Improvements in Guards for Match-Boxes, of which the following is a specification, reference being had to the accompanying drawings.

10 This invention relates to an improved guard for match boxes and has for its primary object to provide a simple, easily applied, and absolutely effective protecting device for the matches which will prevent ignition of the matches contained in the box when one of the matches is scratched on the emery paper or other friction material on the side of the box cover.

15 It is another important object of the invention to provide a device of this character which will effectively prevent the contact of the flame or a spark from an ignited match when inserted into one end of the partly withdrawn cover, as is commonly 20 done in windy weather to prevent the extinction of the flame, thereby obviating the possibility of seriously burning the smoker.

25 It is a further general object of my invention to provide a guard or protecting device for the above purpose which is constructed from a single piece of resilient metal, bent or stamped into such form to enable the same to be readily inserted upon the matches within the box and retain its applied position and permit of easy accessibility to the matches, whereby they may be 30 singly withdrawn from the box.

35 With the above and other objects in view, my invention consists in the novel features 40 of construction, combination and arrangement of parts to be hereinafter more fully described, claimed and illustrated in the accompanying drawing, in which,

45 Figure 1 is a perspective view showing the box partly open and my improved guard or protecting device arranged upon the matches;

50 Fig. 2 is a longitudinal section through the box; and

55 Fig. 3 is an enlarged perspective view of the guard device removed from the box.

Referring in detail to the drawing, B designates the body of a box or container such as is ordinarily used for containing 60 safety matches, and C the cover therefor

which is open at its opposite ends and within which the body of the box snugly fits. This cover, as is usual, is provided upon its opposite side faces with emery paper or other suitable frictional material.

60 The invention constituting the subject-matter of the present application is formed from a single piece of resilient sheet metal and includes the body plate 5 which is of a width substantially equivalent to the interior 65 width of the box body B and is of a length approximately one-half the length of the interior of the box body. Upon one end edge of the body plate 5, the angularly disposed flange 6 is formed by bending the 70 plate, and longitudinally disposed flanges 7 are also formed in a similar manner upon the side edges of said body plate. These latter flanges are of substantially the same 75 length as the interior length of the box 80 body, thereby providing the free end portions 8 projecting beyond one end of the body plate and adapted for clamping engagement against the side walls of the box body. It will be understood that the opposite 85 corners of the sheet metal plate from which the guard is formed, are cut or slit to permit of the bending of the flanges 6 and 7 at right angles to each other.

80 In use, the guard device is arranged within the match box or container as shown in Fig. 1, the flange 6 extending down into the box between one end wall and the heads of the matches. The body plate 5 projects longitudinally over and upon the matches for 90 approximately one-half the length thereof. The side flanges 6 extend between the side walls of the box body and the matches, and in inserting the device, the free resilient end portions 7 of these flanges are slightly 95 pressed inwardly so that when released, they will exert an outward clamping pressure against the side walls of the box, whereby the device will be properly held against casual shifting movement with respect to the 100 box walls. It will thus be seen that the box body may be forced beyond one open end of the cover C to expose the unprotected ends of the matches so that a match can be readily withdrawn. The match head is then 105 scratched upon the friction sheet and the flaming match can be inserted into the opposite end of the cover so that the cover walls will protect the flame and prevent its being blown out. Although the flame is closely 110

adjacent to the end of the box body wherein the match heads are disposed, as the match heads are entirely covered by the sheet metal wall, they will not be ignited by the flame 5 or a spark which might find its way between the top wall of the box cover and the matches. Of course, if the box body is shifted in the cover in the opposite direction and the flaming match disposed within the other 10 end of the cover, there is still less liability of the ignition of the matches. It will thus be seen that I have provided a very simple and at the same time highly effective device which will prevent the accidental ignition 15 of matches contained in the box, thereby obviating possibility of serious burning and injury to the user. After all of the matches have been used, the guard device is, of course, removed and applied in the manner above 20 stated to any box.

From the foregoing description, taken in connection with the accompanying drawing, the construction, manner of use and several advantages of the invention will be clearly 25 and fully understood. The article being formed from a single sheet of metal which may be readily stamped out and properly bent, it will be manifest that the device can be manufactured at very low cost and may, 30 therefore, be given away with the matches by the manufacturer as an advertising novelty, or the guard devices may be separately manufactured and sold. While I have shown and referred to the guard as designed 35 primarily for use in connection with boxes of that type in which small safety matches are usually vended, it is apparent, of course, that the guard can be constructed in various sizes for application to other types of boxes 40 or containers. I do not, therefore, desire to be limited to the application and use of the device as herein disclosed, but reserve the privilege of resorting to various minor changes in the form and construction of its 45 several parts whereby it may be readily applicable to containers of various other forms or constructions.

Having thus fully described my invention,

what I desire to claim and secure by Letters Patent is:

1. A guard device for match boxes consisting of a rectangular metal plate adapted to be arranged over the matches contained in the box and having flanges on its longitudinal edges, a portion of each flange being free 55 for resilient clamping engagement against one of the side walls of the box and said plate also having a flange on one of its ends to extend between the match heads and the opposed end wall of the box. 60

2. A guard device for match boxes consisting of a metal plate adapted to be arranged over the headed end of the matches, said plate being of a length approximately one-half the length of the box and having 65 a flange on one end to extend between the match heads and the end wall of the box, said plate also being provided with additional flanges disposed between the matches and the side walls of the box and having 70 free, resilient portions to clampingly engage against the inner faces of said side walls and retain the plate in its applied position against casual movement with respect to the matches. 75

3. As an improved article of manufacture, a guard device for match boxes formed from a single sheet metal plate to provide a body portion to extend longitudinally over the headed ends of the matches for approximately one-half the length of the box, one end of the plate being bent to provide a flange adapted to extend between the end wall of the box and the match heads, said plate being also bent to provide side flanges, 85 said flanges projecting beyond the opposite end of the body plate and adapted for clamping engagement against the inner faces of the side walls of the box.

In testimony whereof I hereunto affix my 90 signature in the presence of two witnesses.

WILLIAM A. FETSCH.
